(57) **CLAIM**

The ornamental design for a touch panel for scanner with graphical user interface, as shown and described.

DESCRIPTION

FIG. 1 is a front perspective view of a touch panel for scanner with graphical user interface showing our new design; FIG. 2 is a front view thereof;

FIG. 3 is a top plan view thereof; and,

FIG. 4 is an enlarged view of the touch panel thereof. The broken lines in the drawings illustrate unclaimed portions of the scanner and form no part of the claimed design.
